WILLIAM D. CROZIER, OF GENEVA, ILLINOIS, ASSIGNOR, BY MESNE ASSIGNMENTS, TO UNITED REPRODUCERS PATENTS CORPORATION, OF ST. CHARLES, ILLINOIS, A CORPORATION OF NEVADA

ELECTROSTATIC PICK-UP DEVICE

Application filed September 4, 1928. Serial No. 303,721.

The present invention relates to electrostatic or condenser type of pick-up devices, such as those used for talking machines and phonographs and like sound reproducing devices, and with an electrical amplifying device.

Among the objects of the invention is to provide a novel pick-up device of the condenser or electro-static type, and one which will convert impressed mechanical vibrations from a record into electrical energies in consonance with the undulations of the record so as to reproduce sound with ample volume and a faithfulness not peculiar to the usual type of electromagnetic type of pick-up device. The converted energies are preferably impressed upon the grid of an audion tube in an amplifying circuit.

Other objects, advantages, capabilities and features are comprehended by the invention as will later appear and as are inherently possessed thereby.

Referring to the drawings, Fig. 1 shows in a diagrammatic way an embodiment of the invention; and Fig. 2 is a diagrammatic showing of the amplifying circuit.

Referring more particularly to the drawings, the embodiment selected to illustrate the invention is shown in relation to a talking machine or phonograph record 1 having undulated grooves for operating a stylus 2 carried in a stylus holder 3 and suitably secured therein by any suitable means, such as a thumb screw 4. The stylus holder is carried by the end of a bar 5 having a fulcrum 6 on a fixed part 7 of the device. The bar has an upper end 8 to which may be secured, as by soldering an end of a thin flat metal piece 9. This piece may be of thin flat steel, and is designed to be stiff longitudinally, but adapted to have slight flexibility transversely, so as to compensate for the arc movement of the end 8 of the bar 5 when the same is being vibrated or oscillated by the record grooves.

The other end of the part or element 9 may also be soldered or otherwise secured to two or more struts of light weight stiff wires 10 and 11 which lead to and are suitably secured, as by soldering, to the marginal por-

tions of a conducting member 12 of the electro-static pick-up device. This member may be of metal and is made of convex form and may also be hollow in order that it may be very light in weight. The convex side of this member 12 is presented to and is in contact with a thin dielectric sheet or diaphragm 13 held at its margins in fixed parts 14 and 15 of the device. As an example of a dielectric used, rubberized silk or the like may be used. It is to be understood that the invention is not limited thereto, but may comprehend other dielectric materials, such as parchments, paper, sheet rubber and other like and similar materials. It is preferable that this dielectric be flexible. On the opposite side of the dielectric, is provided a flexible coating of conducting material, which may be gold leaf, metal foil, and any other and like suitable conducting material which may be associated with or secured to the face of the dielectric as shown.

The convexity of the surface of the member 12 is such as to provide therebetween a thin divergent air space such that when the member 12 is vibrated and the diaphragm 13 with the conducting surface 16 made to flex, the radially successive points, from the center point of contact on the surface of the member 12 will progressively come into the greater proximity, with the flexible dielectric. In this way, progressive parts of the member 12 will come closer and closer to the surface of the dielectric 13 and thus increase the electro-static stress existing between the conducting member and the dielectric. The conducting part 16 is connected by a wire or conductor 18 and the bar 5 is connected by another wire 19 preferably at a point 20 close to the fulcrum 6. These wires are in the circuit shown in Fig. 2.

Referring to Fig. 2, the amplifying circuit shown as an example, comprises an amplifying tube 20 of the audion type and comprising a plate 21 connected by conductor 22 to an output terminal 23. The circuit continues to an output terminal 24, through a battery 25, conductor 26 connected to one side 27 of the filament circuit of the filament 28, the other side of which is connected to a

conductor 29, it being understood that there is a heating source 30 across the conductors 27 and 29 for heating the filament. The tube also has a grid 31 connected by a conductor 32 leading to a condenser 33 and thence by a conductor 18 or 19 to the electrostatic device A shown in detail in Fig. 1 of the drawings. From this leads the conductor 19 or 18 to the filament conductor 27.

10 Also, in shunt, may also be connected resistances 34 and 35 and batteries 36 and 37, as shown in the diagram of Fig. 2. The value of these resistances, batteries and condensers may be that suitable to obtain the 15 best results from the circuit. As an example, the condenser 33 may be of about one tenth of a microfarad.

The resistance 34 and 35 are preferably of high resistance of at least one megohm and as 20 high as twenty megohms. Battery 36 is preferably of a high voltage battery of about one hundred volts or more. Battery 37 may be of the usual C biasing type of battery to suit the value of the tube used. Battery 25 25 is a usual B battery used in such circuits. It may be replaced by any device for obtaining electrical current from a supply circuit. The capacity of the electro-static device A may be but a few micro-microfarads.

30 In operation, the record will cause the bar 5, by the way of stylus 2, to vibrate and this vibration will be transmitted to the longitudinally stiff member 9 and through the stiff wires or struts 10 and 11 to the metal member

35 12. This will cause the metal member to press more or less against the dielectric 13 and cause the same to flex in proportion therewith. The coating 16 will also flex with the dielectric. This vibration will cause the 40 electrostatic stresses to vary in proportion to the vibrations set up, and the impressed electrical energies will pass through the circuit and be impressed upon the grid 31 as also upon the plate 21. It is to be understood

45 that although one stage of amplification is shown in Fig. 2 that other stages may be added in accordance with the usual circuit. As the member 12 is vibrated, points located 50 radially outwardly of the center point of contact will come into progressive contact with the diaphragm 13 as it is flexed and thus increase the electrostatic attraction in the electrostatic device. Reflex action will act

55 similarly for the decreased electrostatic potential. This will cause a fluctuation or a series of impulses in the electrical line in proportion to the undulations in the record 1.

While I have herein described and upon 60 the drawings shown an illustrative embodiment of the invention, it is to be understood that the invention is not limited thereto, but may comprehend other constructions, arrangements of parts, details, and features 65 without departing from the spirit thereof.

Having thus disclosed the invention, I claim:

1. An electrostatic pick-up device comprising a flexible dielectric member having a conducting surface, a movable conducting member associated with the opposite surface of said dielectric member, and means associated with the conducting member to move it in accordance with the undulations of a record. 70

2. An electrostatic pick-up device comprising a flexible dielectric member having a conducting surface, a movable conducting member having a curved surface proximate to the opposite surface of said dielectric member, and means associated with the conducting member to move it in accordance with the undulations of a record. 75

80 3. An electrostatic pick-up device comprising a flexible dielectric member having a conducting surface, a movable conducting member having a convex surface adjacent the opposite surface of said dielectric member, and means associated with the conducting member to move it in accordance with the undulations of a record. 85

90 4. An electrostatic pick-up device comprising a thin flexible diaphragm of dielectric material, a flexible metal coating on one of the surfaces of the diaphragm, a metal member contacting the other of said surfaces of the diaphragm, and means to vibrate said member and flex said diaphragm in accordance with a sound record. 95

100 5. An electrostatic pick-up device comprising a thin flexible diaphragm of dielectric material, a flexible metal coating on one of the surfaces of the diaphragm, a metal member having a convex surface contacting the other of said surfaces of the diaphragm, and means to vibrate said member and flex said diaphragm in accordance with a sound record. 105

110 6. In an electrostatic pick-up device provided with a flexible dielectric member having a conducting surface, a conducting member adapted to contact the non-conducting surface of the dielectric, a stylus operated member, and a thin element connecting said stylus operated member and said conducting element for transmitting vibratory movement 115 to said conducting member, said element being stiff in its direction of movement transmission and flexible in a transverse direction.

120 7. In an electrostatic pick-up device provided with a flexible dielectric member having a conducting surface, a conducting member adapted to contact the non-conducting surface of the dielectric, said conducting member comprising a convex element adapted to present its convexity to said dielectric, 125 and a strut connected to said element and to a stylus operated means.

130 8. In an electrostatic pick-up device provided with a flexible dielectric member having a conducting surface, a conducting mem-

ber adapted to contact the non-conducting surface of the dielectric, said conducting member comprising a convex element adapted to present its convexity to said dielectric, a 5 strut having an end rigid with said element, a movement transmitting part connected to the other end of the strut and to a stylus operated means.

9. In an electrostatic pick-up device provided with a flexible dielectric member having a conducting surface, a conducting member adapted to contact the non-conducting surface of the dielectric, said conducting member comprising a convex element adapted to present its convexity to said dielectric, a strut having an end rigid with said element, a thin flat metal part connected to the other end of the strut and to a stylus operated means.

10. An electrostatic pick-up device comprising a pair of conducting elements and a thin dielectric therebetween, one of said conducting elements being movable, and means operated by a sound record and connected to 5 said movable conducting element to vibrate the same, said dielectric and the other of said conducting elements being flexible.

In witness whereof, I hereunto subscribe my name to this specification.

WILLIAM D. CROZIER.
